UNITED STATES PATENT OFFICE.

HARRY LE VAN HORNING, OF WAUKESHA, WISCONSIN, ASSIGNOR TO WAUKESHA MOTOR COMPANY, OF WAUKESHA, WISCONSIN, A CORPORATION OF WISCONSIN.

CONDENSER STRUCTURE.

Application filed August 25, 1926. Serial No. 131,331.

My invention relates to condenser structures which are of particular utility in steam cooling systems for internal combustion engines for condensing the steam resulting from the heating of the water in the engine cylinder jackets. The object of the invention is to provide improved arrangement for creating natural draft for cooling air circulation along the surfaces of ducts or chambers through which the steam to be condensed is flowing. In general, the structure comprises the arrangement of condenser sections, concentrically or otherwise, and spaced apart to form passageways through which heated air may rise to create circulation of cooling air.

On the drawing, Figure 1 is a side elevational view of a condenser structure incorporating my invention and applied in a cooling system such as that disclosed in the copending application of Arthur W. Pope, Jr., Serial No. 131,377, filed August 25, 1926; and

Fig. 2 shows a modified arrangement. In Fig. 1, E represents an internal combustion engine having the water jacket 10 surrounding the cylinder 11. The water tank 12 may be of circular, polygonal, or any other desired cross section. The drawing shows it of circular cross section and inserted therein but spaced away therefrom is the inner shell 13 which may have the upper flange 14 extending around the upper edge of the tank so that the annular steam or condenser chamber 15 between the tank and the shell will be closed at the top. The lower edge of the shell 13 terminates a distance above the bottom of the water tank so that the annular condenser chamber may communicate with the space 16 inside of the shell. This space 16 together with the space between it and the tank bottom forms a water reservoir which is closed at the top by a cover structure 17 which may be conical as shown and which at its apex has the steam vent 18. Preferably cooling fins 19 are provided on the cover structure to increase the condensation and cooling surface.

Surrounding the steam or condenser chamber 15 is the annular condenser or steam

chamber 20. This outer chamber is spaced away from the chamber 15 to leave the air passageway 21 and as shown this outer chamber is frusto-conical with its largest diameter at the top so that the passageway 21 will have an increasing cross section area upwardly. At intervals the inner and outer steam chambers 15 and 20 are connected at their upper ends by pipes or conduits 22, while pipes or conduits 23 connect the chambers at their lower ends at intervals.

In the arrangement shown the steam outlet pipe 24 extends from the top of the water jacket 10 to the top of the outer steam chamber 20, although the connection could be 65 with the inner steam chamber. The lower end of the water jacket is connected by the pipe 25 with the bottom of the water reservoir 16.

The normal water level, that is, when the engine is cold, is indicated by the line *a—a*. The steam pipe 24 entering the steam chambers above this level and the cross connecting pipes 22 being also above this level. When the engine is started there is therefore 75 no circulation of water through the cylinder jacket and consequently, the water in the jacket will soon be heated to the boiling or steam generating point. As the steam is formed in the jacket it rises in the pipe 24 80 and flows into the outer steam chamber 20 and through cross connection pipes 22 into the inner steam chamber 15. As the quantity of steam increases the generated pressure will force the water in the steam or condenser chamber downwardly and as soon as the water is forced down to the level of the lower edge of the shell 13, an equilibrium point will be reached and thereafter, any surplus steam will flow upwardly around 85 the lower edge of the shell and through the water in space 16, any uncondensed steam then striking the finned cover structure 17 for further condensation, the residue steam escaping through the vent 18. In 90 the travel of the steam from the engine to the vent 18 the steam in the steam chambers is first subjected to the cooling influence of the air circulating between the chambers through the passageway 21. When the 95 100

steam enters the chambers the air in the space 21 is heated and rises and so establishes a continuous circulation upwardly through the passageway along the walls of 5 the chambers and considerable condensation of the steam takes place in the steam or condenser chambers. There is also more or less condensation in the outlet pipe 24 which is surrounded by the atmosphere. The steam 10 flowing to the inner chamber 15 is also subjected to the wall or shell 13 cooled by the water within the space 16 and considerable condensation takes place. The remaining steam then flows through the water in 15 the space 16 and whatever steam is left will strike the extensive surface of the cover structure so that only a very small amount, if any, of steam will ever reach the vent 18. The condenser structure can be dimensioned 20 so that the loss of water in the form of steam will be practically negligible. The condensed steam is added to the water in the reservoir which feeds to the water jacket of the engine. Instead of the two concentric 25 steam or condenser chambers shown, there may be a greater number with air circulating passageways between them. The supply of cooling water can also be increased by increasing the depth of the tank 12. 30 In the modified arrangement of Fig. 2, the condenser structure is separate from the water supply space or reservoir 26. The condenser structure comprises a series or tier 35 of condenser chambers or sections 27. As shown these sections are parallel and tilted at an angle so that there is a natural draft of air between them from the lower toward the higher end. At their ends the condenser sections are connected by headers 28 and 29 40 respectively. At its lower corner the condenser structure is connected by pipe 30 with the lower end of the water tank and the upper corner of the condenser structure is connected by pipe 31 with the upper end 45 of the engine water jacket. A pipe 32 connects from the bottom of the water tank to the lower end of the water jacket. The engine is not shown in Fig. 2, but the connections of the pipes 31 and 32 with the 50 engine are the same as the connections in the pipes 24 and 25 in the arrangement of Fig. 1. The steam flows from the engine jacket through the condenser sections where it is subjected to the cooling influence of the air 55 flowing through the passageways between the sections, the uncondensed steam flowing through connection 30 into the tank 26 and through the water therein to be finally condensed. Any wind, either natural or forced, 60 toward the low end of the condenser sections will increase the circulation of air between the sections and thereby increase the condensing efficiency. Under ordinary conditions, however, the natural draft will be 65 sufficient to give the desired condensation.

Having described my invention, I claim as follows:

1. In a condenser structure, the combination of a water reservoir, steam chambers surrounding said water reservoir and spaced apart for the circulation of air, a steam inlet at the upper ends of said steam chambers, said chambers being connected at their lower ends with said water reservoir, and a water outlet from the lower part of said water reservoir. 70
2. In a condenser structure, the combination of a plurality of condenser sections spaced apart for the natural draft of air between them, said sections being connected together at their ends, a steam inlet at one end of said sections and a water inlet at the other end thereof, and a water reservoir connected to said water inlet. 80
3. In a condenser structure, the combination of a water reservoir, a plurality of steam chambers concentric with said reservoir, said chambers at their lower ends being connected with the water reservoir, and a water outlet from said reservoir below said stream chambers. 85
4. In a condenser structure, the combination of a plurality of condenser sections spaced apart to form passageways for the natural draft of cooling air, a water reservoir connected with the lower ends of said sections for supplying water thereto, and a steam connection for the upper ends of said sections for conducting steam thereto, said water reservoir receiving the steam from said condenser sections and condensing it. 90
5. In a condenser structure, the combination of a vertical water reservoir, a plurality of condenser sections concentric with said reservoir, said sections communicating at their lower ends with the water reservoir and at their upper ends having a steam inlet, and a water outlet from the lower end of said water reservoir, said condenser sections being spaced apart for the upward flow of cooling air therebetween, said air space being of increasing cross sectional area upwardly. 105
6. In a condenser structure, the combination of a water tank, a shell within said tank forming a water reservoir and spaced therefrom to form a steam chamber closed at its top but open at its lower end to said water reservoir, an additional steam chamber surrounding said water reservoir and spaced from the first mentioned steam chamber to leave a space for the circulation of cooling air, said additional steam chamber communicating at its lower end with said water reservoir, a steam inlet for the upper end of said steam chambers, and a water outlet from said reservoir. 115
7. In a condenser structure, the combination of a water tank, a shell within said tank forming a water reservoir and spaced therefrom to form a steam chamber closed at its 120
- 125
- 130

top but open at its lower ends to said water reservoir, an additional steam chamber surrounding said water reservoir and spaced from the first mentioned steam chamber to leave a space for the circulation of cooling air, said additional steam chamber communicating at its lower end with said water reser-

voir, a steam inlet for the upper end of said steam chambers, and a water outlet from said reservoir, said air space being divergent ¹⁰ upwardly.

In witness whereof, I hereunto subscribe my name this 20th day of August, 1926.

HARRY LE VAN HORNING.
